UNITED STATES PATENT OFFICE.

AARON W. GILMORE, OF TYLER, TEXAS.

TRUSS.

1,175,144.

Specification of Letters Patent. Patented Mar. 14, 1916.

Application filed January 15, 1915. Serial No. 2,330.

To all whom it may concern:

Be it known that I, AARON W. GILMORE, citizen of the United States, residing at Tyler, in the county of Smith and State of Texas, have invented certain new and useful Improvements in Trusses, of which the following is a specification.

This invention relates to new and useful improvements in trusses.

The object of the invention is to provide a truss involving a pair of spring hangers each carrying a pad of particular construction and arrangement.

Another object is to provide a pad equipped with a retaining device whereby a cloth or other flexible material may be easily and expeditiously fastened over the pad.

A further feature resides in provision of means for rotatably adjusting the pads whereby they may be disposed at an angle comfortable to the wearer.

A still further object of the invention is to provide a device of the character described that will be strong, durable, efficient, and simple and inexpensive to construct, also one in which the several parts will not be likely to get out of working order.

With the above and other objects in view the invention has relation to certain novel features of construction and operation, an example of which is described in the following specification and illustrated in the accompanying drawings, wherein:

Figure 1 is a perspective view of the truss, Fig. 2 is a front view of one of the pads, Fig. 3 is an underside view of said pad, and Fig. 4 is a cross sectional view taken on the line $x-x$ of Fig. 2.

In the drawings the numeral 1 designates a spring hanger of which two are employed. The hangers are preferably formed of spring steel wire of about number ten gage, although this may be varied. The hangers are shaped to fit over the hips of the wearer, one on each side. Each hanger has a ring-like portion 2 at its rear end. These portions are connected by a flexible member 3 and over each portion 2 a flexible pad 4 is sewed, the parts 3 and 4 being sewed together and preferably formed of leather. The front end of each hanger terminates in a ring 5 and as they are duplicates, a description of one will suffice for both. The ring 5 is securely fastened to the hanger and provided with an inwardly directed annular flange 6 as is best shown in Fig. 4. A metal

disk 7 fits in the ring on the flange so as to be rotated. A pad 8 of suitable material has on its front side a circular boss 9 which has a rotating fit in the flange 6 which rests on the pad around the boss. A stud 10 has a squared portion embedded in the pad 8, but that portion projecting beyond the boss is round and threaded. The stud passes through the disk 7 and receives a cap nut 11. When the cap nut is screwed up against the disk 7 the boss 9 is drawn into the flange and the pad 8 caused to bind against the flange and ring, said pad thus being fastened in position. It is obvious that by loosening the nut 11 the pad may be rotated and as said pad has an elongated shape, it may be adjusted to suit the fancy and comfort of the wearer. The cap nut has a rounded head and an external annular groove 12. A strap 14 is provided with slits 15 in which the nut may be engaged so that the strap rests in the groove.

The pad 8 is provided with a marginal flange 16 on which a clamp-frame 17 is disposed. This clamp-frame has substantially the same shape as the pad 8, is slightly larger, and rests at the base of said pad. At one end the clamp-frame is attached to a hinge 18 which is secured to the pad; while at the opposite end the pad has a spring catch 19 which projects and normally holds the clamp-frame in position. The pad is recessed about the catch so that the latter may be sprung inward. Opposite the catch the clamp-frame has a finger lug 20. One may use the lug in swinging the clamp-frame outward as shown in dotted lines in Fig. 4. With the clamp-frame swung outward a piece of cloth or leather may be placed over the pad as shown at A in Figs. 1 and 4, and the clamp-frame is swung into normal or closed position said material A will be clamped and held smoothly over the pad. It is obvious that the material A may be readily applied and replaced, or the pad may be used without it. The clamp-frame is quickly opened and closed and does not interfere with the effectiveness of the pad.

In Fig. 1 the pads 8 are shown connected by the strap 14 which is left permanently on one of the nuts 11 and buttoned over the other nut after the truss has been positioned on the body of the wearer. The resilient nature of the hangers, the flexible connections 3 and 14 and the adjustable

pads 8 constitute a truss which will readily adapt itself to the contours to which it is applied. The adjustment in the rings 5 enables the wearer to turn the pads 8 so that they contact at the desired angle.

What I claim, is:

In a truss, a supporting member constructed to engage the body of the wearer, a ring fixed on the end of the support, a 10 pad having a boss projecting into the ring and rotatable therein, a disk disposed in the

ring, a clamp engaging the disk and the pad and binding the latter against the ring, and a cloth clamping frame hinged on the pad and swinging over the face of the same. 15

In testimony whereof I affix my signature in presence of two witnesses.

AARON W. GILMORE.
